UNITED STATES PATENT OFFICE.

WILLIAM LOEVEN, OF CHICAGO, ILLINOIS.

DESIGN FOR A TABLE.

SPECIFICATION forming part of Design No. 34,870, dated July 30, 1901.

Application filed June 17, 1901. Serial No. 64,965. Term of patent 3½ years.

To all whom it may concern:

Be it known that I, WILLIAM LOEVEN, a citizen of the United States, residing at Chicago, in the county of Cook and State of Illinois, have invented and produced a new and original Design for Tables, of which the following is a specification, reference being had to the accompanying drawings, forming part thereof.

10 Figure 1 is a perspective view of a table, showing my new design; and Fig. 2 is a central vertical sectional view.

As shown in the drawings, the material feature of my design consists of a base A, having four legs *a*, united together at the middle upper portion of the base by horizontal parts *a'*. The central portion of the base A is formed with a downward cylindrical extension *b*, and each of the legs *a* and horizontal portions *a'* are T-shaped in cross-section. The bottom of each of the legs is provided with a foot *c*, which extends outwardly. Extending upwardly from the extension *b* is a rod or standard B, which is formed with annular grooves *b'* and beads *b''* near its upper

end and also intermediate of its ends. The rod or standard B is also formed with reduced portions *d*. On the upper end of the standard B is a circular platform C, which has an upwardly-extending annular flange *c'* on its 30 periphery. Located on the lower portion of the standard B, just above the base A, is another platform D, which has an upwardly-extending annular flange *c''* on its periphery. On the central lower portion of the platform 35 D is located a circular piece or plate E, which has a downward extension surrounding the standard.

Having described my invention, what I claim as new, and desire to secure by Letters 40 Patent, is—

The design for a table, substantially as herein shown and described.

In testimony whereof I have signed my name to this specification in the presence of 45 two subscribing witnesses.

WILLIAM LOEVEN.
